CLARENCE H. WILKES AND GEORGE E. CALHOUN, OF AMSTERDAM, NEW YORK, AS-SIGNORS TO AMSTERDAM CUTLERY COMPANY, INCORPORATED, OF AMSTERDAM, NEW YORK, A CORPORATION OF NEW YORK.

SHEARS.

Application filed May 26, 1925. Serial No. 32,911.

This invention relates to certain improvements in shears and more particularly to hand shears in which a pair of levers crossing each other are pivoted together at the crossings and are provided at one end with suitable blades and at their other ends with handles by which the blades may be opened and closed for cutting purposes.

In shears of this character each lever is usually forged or otherwise molded from a single piece of suitable cutlery steel in such manner that the cutting edges of the blades are generally considerably thinner than the back edges and beveled in opposite directions so as to form the desired cutting edges and owing to this fact it is not always possible to produce a uniform hardening or tempering of all portions of the cutting edges in that some portions thereof may be too hard and brittle and other portions too soft resulting in differential wearing and lack of uniformity in grinding or sharpening.

Furthermore when the cutting edges are formed directly upon the blades of the one piece levers it is more or less difficult to grind or sharpen the cutting edges uniformly without separating the levers at their crossings and grinding one blade at a time and it, therefore, follows that after a greater or less period of use and frequent re-sharpening the cutting edges become deformed and unfit for further use resulting in the discard of the entire shears and replacement by a new set.

The main object of our present invention is to overcome these difficulties by providing extra comparatively thin cutting blades of uniform thickness throughout their lengths capable of being more easily and uniformly tempered or hardened throughout their areas and applying them to the blades of the levers in such manner that they may be readily placed and locked in operative position and easily and quickly removed when desired for sharpening so that when worn or otherwise impaired beyond further use they may be replaced by new ones upon the same blades of the levers at a comparatively low cost, thus permitting the use of both levers for an indefinite period of time.

It is also well-known that in shears of this type as usually constructed the pivotal connection at the crossing soon becomes worn

and loosened to such an extent as to render the cutting operation more or less inefficient and to require frequent tightening which cannot always be adjusted to the required nicety, and another object is to provide the heel of one of the blades with a return extension adapted to overlap upon the outer face of the adjacent portion of the other blade for receiving the pivotal screw and for the purpose of retaining said blades in closer operative relation for a longer period of time than has heretofore been possible.

Other objects and uses relating to specific parts of the device will be brought out in the following description.

In the drawings:

Figures 1 and 2 are opposite face views of a pair of shears embodying the various features of our invention, portions of one of the handles in Figure 2 being broken away.

Figure 3 is an enlarged longitudinal vertical sectional view thru the blades of the shears taken on line 3—3, Figure 1.

Figure 4 is an enlarged transverse sectional view thru the blades taken on line 4—4, Figure 1.

Figures 5 and 6 are face views of the detached supplemental blades.

Figure 7 is an enlarged longitudinal sectional view through a portion of one of the levers and adjacent portion of one of the shearing blades, the latter being shown by dotted lines as detached.

As illustrated, this shears comprises a pair of levers 1 and 2 crossing each other intermediate their ends to form opposed blades —3— and —4— at one end and suitable handles —5— and —6— at their opposite ends, said levers being provided with registering apertures —7— and —8— at their crossings for receiving a pivotal pin or stud —9— whereby the levers are pivotally connected to each other.

The handle ends —5— and —6— of the levers are offset outwardly from the longitudinal centers of their respective blades —4— to form an intervening space between them extending to a point in more or less close proximity to the crossing portions of the levers, the heel of one of said levers as —3— being provided with a U-shaped extension —10— integral therewith and returned a limited distance toward the point

of the blades so as to overlap upon the outer face of the adjacent portion of the other blade —4— beyond the pivot —9—.

The base of the U-shaped extension —10— ⁵ extends across the heel of the blade —4— in the space between the adjacent portions of the handles —5— and —6—, the relative widths of the base of the extension —10— and space between the adjacent portions of ¹⁰ the handles being sufficiently different to permit the levers to open and close without friction with the base of the extension.

The forwardly returned arm of the extension —10— is provided with an aperture ¹⁵ —11— for receiving the head of the pivotal bolt —10— and is also parallel with the opposite portion of the blade —3— and tensioned so as to exert axial pressure upon the crossing portions of the blades, one against ²⁰ the other, to hold their cutting blades, presently described, in cutting relation, it being understood that these levers will be made of cutlery steel or equivalent material having more or less resiliency.

²⁵ The adjacent or inner faces of the blades —3— and —4— are substantially flat transversely throughout their lengths for receiving and supporting a pair of cooperative shearing or cutting blades —13— and —14— ³⁰ which are preferably made of comparatively thin sheets of cutlery steel or uniform thickness and tempered to the required degree of hardness for cutting purposes.

Each supplemental cutting blade —13— ³⁵ and —14— is of substantially the same form as its supporting blade —3— and —4— so as to extend from the pivot —9— to the points thereof and is assembled thereon in such manner that its cutting edge projects beyond the adjacent edge of the supporting blade throughout the length thereof for cutting purposes, said cutting edges of the blade —13— and —14— being slightly convexed longitudinally as shown in Figures 1 and 2 ⁴⁰ and also beveled transversely as shown in Figure 4 to form cooperative shearing edges —13'— and —14'—.

Suitable means is provided for detachably or removably retaining the supplemental blades —13— and —14— in operative position upon the inner faces of their supporting blades —3— and —4— and for this purpose each of the supporting blades —3— and —4— is provided with two or more studs ⁵⁰ —15— rigidly and permanently secured thereto in spaced longitudinal relation some distance from the pivotal pin —9— and extended beyond the inner face of the supporting blade a distance corresponding approximately to, but not greater than the thickness of the adjacent supplemental cutting blade —13— or —14—.

The inner end of each stud —15— is enlarged and preferably flared inwardly to ⁶⁰ form a head —15'— so that the periphery

thereof is more or less undercut to form a retaining shoulder for the adjacent supplemental cutting blade as —13— or —14— in a manner presently described.

These supplemental cutting blades —13— ⁷⁰ and —14— extend from points slightly beyond the points of the supporting blades —3— and —4— along the inner faces of said supporting blades and beyond the pivotal pin —9— so that their adjacent inner ends cross and overlap one upon the other between the adjacent portions of said supporting blades and are provided with registering apertures —16— for receiving the pivotal pin —9—, the tension of the forwardly extending arm of the extension ⁸⁰ —10— serving to hold the meeting faces of the supplemental blades —13— and —14— in close cutting relation.

Each of the supplemental cutting blades ⁸⁵ —13— and —14— is also provided with two or more holes or openings —17— arranged in longitudinally spaced relation corresponding approximately to the spacing of the heads —15'— of the studs —15— and are also ⁹⁰ flared inwardly preferably by counterboring to form beveled shoulders —17'— for interlocking engagement with the heads —15'— of the adjacent supporting blade —3— or —4—.

The smaller ends of the openings —17— are somewhat larger than the heads —15'— to permit the latter to pass easily therethrough when assembling or removing the supplemental blades. ¹⁰⁰

The distances between the axis of the pivotal opening —16— and axes of the holes —17— in each blade are slightly less than the distances between the axis of the pivotal stud —9— and blade retaining studs —15— ¹⁰⁵ so that when the supplemental blades —13— and —14— are placed upon the inner faces of their respective supporting blades —3— and —4— with their openings —17— registering with the heads —15'— of their corresponding studs —15— and then moved endwise toward their respective handles —5— and —6— the beveled shoulders —17'— will interlock with the heads —15'— while their pivotal openings —16— will simultaneously register with the openings —7—, —8—, and —11— in the parts —3—, —4—, and —10— for receiving the pivot —9— which, when inserted in the openings —7—, —8—, —11— and —16— will hold ¹¹⁵ the supplemental blades —13— and —14— in interlocking engagement with the heads —15'— of the studs —15—.

The opening —7— in the lever —1— is threaded while the adjacent end of the pivotal bolt —9— is reduced and also threaded for engagement with the threaded aperture —7—, the reduced threaded end forming a shoulder —9'— which when the pivotal stud —9— is tightened engages the inner face of ¹²⁵ —10—.

the lever —3— to firmly hold the stud in fixed position and also to prevent excessive tightening of the levers —1— and —2— and cutting blades —13— and —14— at their 5 crossings.

Operation.

Assuming that the pivotal pin —9— is removed and that the levers —1— and —2— 10 are separated ready to receive the supplemental cutting blades —13— and —14—, each supplemental blade is then placed flatwise upon its supporting blade with its openings —17— registering with the heads of 15 the corresponding studs —15— after which the supplemental cutting blade is moved endwise by hand toward the corresponding handle until its shoulders —17'— are interlocked with the corresponding heads —15'— 20 at which time the opening —16— will be registered with the pivotal opening in the corresponding supporting blade.

The lever —2— with its cutting blade thereon is then inserted between the forwardly projecting arm of the extension —10— and adjacent portion of the lever —3— and its opening —8— brought into registration with the openings —7— and —11— whereupon the pivotal bolt —9— is 25 inserted into the registering openings —11—, —8—, —16— and —7— and tightened for pivotally connecting the supporting blades —3— and —4— and supplemental cutting blades —13— and —14— to each other and 30 also for holding the supplemental cutting blades —13— and —14— in engagement with their locking members —15'— it being understood that the openings —16— in the supplemental cutting blades —13— and —14— and also the opening —8— in the supporting blade —4— are of substantially 35 the same diameter as the adjacent portion of

the pivotal stud —9— to hold those parts in co-axial relation with the pivotal bolt and also to assure the retention of the supplemental cutting blades —13— and —14— in 45 interlocking engagement with the heads —15'—.

When it is necessary to remove the supplemental cutting blades for re-grinding or for 50 replacement it is simply necessary to remove the screw stud —9— whereupon the supporting blades —3— and —4— may be separated from each other and the cutting blades —13— and —14— removed by end- 55 wise and lateral displacement from their supporting blades —3— and —4—.

What we claim is:

In shears of the class described, a pair of levers crossing each other to form blade-supporting arms at one end and handles at the opposite end, separate shearing blades removably mounted on adjacent faces of said arms and extending across the intersection of the levers to overlap at the crossing, one of said levers having an extension across the overlapping ends of the shearing blades and upon the outer face of the adjacent portion of the other lever to bind the intersecting portions of said levers and overlapping portions of the blades together, a pivotal pin passing through registering openings in said levers, blades and extension for holding the levers and blades co-axial with the pivotal pin, and additional devices 60 for holding the blades against lateral movement relatively to their respective levers when engaged with said pivotal pin and for releasing the blades when the pivotal pin is 65 removed.

In witness whereof we have hereunto set our hands this 20th day of May 1925.

CLARENCE H. WILKES.
